UNITED STATES PATENT OFFICE.

JULIUS E. JARGSTORFF, OF NEW YORK, N. Y.

GAS-BURNER AND AUTOMATIC CUT-OFF THEREFOR.

1,140,161.

Specification of Letters Patent.

Patented May 18, 1915.

Application filed July 27, 1914. Serial No. 853,413.

To all whom it may concern:

Be it known that I, JULIUS E. JARGSTORFF, a citizen of the United States, and a resident of the city of New York, Jamaica, 5 borough of Queens, in the county of Queens and State of New York, have invented a new and Improved Gas-Burner and Automatic Cut-Off Therefor, of which the following is a full, clear, and exact description.

10 This invention relates to an improved gas burner and automatic cut-off therefor designed to automatically cut off the flow of gas whenever the flame from any cause becomes extinguished other than by means of the usual cut-off or gas cock controlling the supply to the burner.

15 The primary object of the invention is to provide a simple, novel and positively operable cutoff which will prevent asphyxiation or other serious complications or occurrences due to the escape of gas into a room or building resulting from a failure or stoppage in the supply of gas from the main at a time 20 when the burners are lighted, from blowing out the gas or by accidental failure to properly cut off the supply of gas to the burners in such a manner as to permit the gas to escape therefrom.

25 30 With the above and other objects in view, the invention resides in the peculiar combination and arrangement of parts to be hereinafter more fully described, illustrated and claimed, it being also an object to provide a device which is simple in construction, durable and efficient in operation and not likely to get out of order.

35 40 Reference is to be had to the accompanying drawings forming a part of this specification, in which similar characters of reference indicate corresponding parts in all the views, and in which—

45 Figure 1 is a vertical sectional view of my improved gas burner and automatic cut-off applied to a burner pipe, the parts being shown in the positions they assume when the burner is lighted; Fig. 2 is a similar view but showing the positions of the parts when the burner is extinguished; Fig. 3 is a horizontal sectional view taken on the line 3—3 50 of Fig. 2; Fig. 4 is a detail perspective view of parts of the thermos valve actuating device for controlling the supply of gas to the burner.

55 In recapitulation, it is submitted that the idea of the device is to prevent the escape

of gas in the event that the light is blown out or the supply of the main is cut out without closing the usual gas cock or cut-off, thus preventing asphyxiation or the escape 60 of gas continuously thereafter, and for this purpose a gas pipe 10 is illustrated carrying the usual gas cock or cut-off 11 for controlling the gas supply to the burner in the usual manner. The burner is in the form of 65 a sheet or rolled metal casing 12 enlarged at its upper end and having a reduced depending portion or neck 13 fitting the burner pipe and removably supported thereon as through the instrumentality of a flange or 70 shoulder 14. A plate 15 is crimped or otherwise secured to the top of the casing 12, as shown at 16, and in such a manner as to form an airtight union preventing the escape of gas from between the joint, it being understood that the gas supply through 75 the pipe 10 when the cut-off 11 is open will entirely fill the interior of the casing. The plate 15 forming the top of the casing is provided with an opening 17 to one side of 80 the center from which projects an inwardly extending sleeve 18 produced by stamping out a portion of the plate and drawing the same inwardly from the metal which is so stamped or punched in so as to adapt the 85 sleeve to receive a burner tip 19 of any well known or improved design. A smaller tube 20 is also drawn from the top portion of the casing by punching the same in and drawing out the tube to the required thickness and length or attaching the same there- 90 to, the tube 20 being located diametrically opposite to the tube 18 and being of smaller diameter and depending the same distance into the casing. 95

Mounted in the casing for vertical movement is a valve disk 21 formed with or carrying a vertical extension 22 which is pref- 100 erably of frusto-conical outline and so po- sitioned as to enter the bottom of the tube 18 and to hold the disk valve from rotation by contact with the inner surface of said tube and guide the disk in its vertical move- 105 ments. The valve loosely fits in the casing to permit the gas to escape therearound into the tube 18 and through the burner tip to be lighted for throwing off light or heat as occasion requires. Mounted upon the disk is a gasket or valve packing 23 which may be of rubber or any other material which 110 will produce an airtight joint by contact with the lower end of the tube 18 under the

action of an expansible coiled spring 24 mounted beneath the disk and engaging the bottom of the enlargement of the casing around the reduced portion or neck 13, but 5 which is not materially affected, deteriorated or decomposed by the gas.

Disposed to operate in the tube 20 is a pin 25 which has a reduced portion 26 at its lower end forming a downwardly facing 10 shoulder 27 to limit the downward displacement of the pin by contact with the upper face of the plate 15 forming the top of the casing and also to prevent the escape of gas from between the tube 20 and the pin. 15 It is also understood that the lower ends of the tubes are normally closed by the gasket on the disk or valve 21 under the action of the spring 24, as is clearly shown in Fig. 2 of the drawings, when the gas escaping from 20 the burner tip is not ignited.

Removably attached for vertical adjustment at one side of the enlarged portion 12 of the casing of the burner is an angular bracket 28 having a slotted lower end, as 25 shown at 29, also bent at an angle, the slot being open at its lower end to permit the bracket to be freely attached and adjusted with respect to the casing through the instrumentality of a set screw 30 threaded in 30 the casing at one side of the latter corresponding to the disposition of the tube 20 and in alinement with both of the tubes. The bracket thus extends upwardly and outwardly and is provided with a horizontal 35 overhanging bar 31 which carries a thermo-controlled device consisting of an expansible element or strip 32 which is held in position between two stamped-out or offset tongues 33 bent downwardly from the overhanging 40 portions 31 and extending toward each other in opposite directions. The bracket is made of material which is not readily sensitive to heat or which has a low coefficient of expansion, while the element or strip 32 is 45 adapted to readily expand under heat or has a high coefficient of expansion, and being held between the tongues its expansion is restricted generally to the central part between the tongues 33.

50 In the operation of the device, when the gas is turned off and the element or strip 32 is cool, the valve under the action of the spring 24 will be held upwardly to close the lower ends of the tubes 18 and 20, although the 55 pin 25 is made to fit the tube 20 sufficiently tight to prevent the escape of gas between the two. As the extension 22 simply acts as a guide to insure positive seating of the valve and to prevent movement thereof, the 60 escape of gas will be prevented, and as the pin 25 is disposed between the valve and the expansible element or strip 32, the pin will be held upwardly displaced and in contact with said strip. By holding a torch or 65 lighted match to the expansible element or

strip the latter will be caused to expand and bulge downwardly, as shown in Fig. 1 of the drawings, so as to depress the valve and open the same against the action of the spring 24 by exerting downward pressure 70 thereon through the instrumentality of the pin 25, and in this manner permit the escape of gas around the extension 22 and through the tube 18 to the burner to be ignited. If, however, the gas should be extinguished 75 without turning off the supply, the strip will cool and move to the position shown in Fig. 2 so as to permit the valve to again close under the action of the spring and prevent further escape of the gas and consequently 80 obviate all danger or accidents which might otherwise occur.

The expansible element or strip 32 is secured or anchored at its ends to the tongues 33, as by means of rivets 34, the purpose of 85 this being to prevent expansion of the strip at its ends, as well as to prevent displacement thereof.

Having thus described my invention, what I claim as new and desire to secure by Letters Patent is:—

1. A gas burner and automatic cutoff therefor, comprising a casing adapted for application to a burner pipe, a pair of independent tubes depending from the edge 95 of the casing and into the same at equi-distances, a burner tip in one of the tubes, a pin in the other tube, a horizontally disposed expansible element adjustably supported above the pin and having a restricted 100 expansible area, means in the casing acting against the pin to raise the same as far as the lower end of its containing tube and simultaneously closing the lower ends of the tube at spaced points, said expansible element upon being heated being adapted to expand to move said tube closing means through the instrumentality of the pin to unseat the same and permit the escape of 105 gas through the tube for ignition and means 110 to hold the closing means for the lower ends of the tube against rotation.

2. The combination with a supply pipe having a cut-off and a shell having a reduced portion fitted to the pipe, said shell 115 having a top portion with a pair of openings therethrough; of a burner fitted in one opening, an expansible element supported by the casing above the other opening for movement downward when expanded, a 120 spring-pressed valve in the casing for normally closing the openings, and vertically operable means between the expansible element and the valve for depressing and opening the latter upon heat being applied to 125 said element to expand the same, whereby gas will escape to the burner to be lighted.

3. A burner and automatic cut-off for gas as described, comprising a sheet metal casing having a central neck portion depending 130

therefrom, a plate clamped to the top of the casing and having a pair of depending tubes drawn therefrom to either side of its center, a tip in one of said tubes, a pin in the other 5 of said tubes and having a reduced portion forming a shoulder limiting its downward displacement, a valve disk loosely mounted in the casing and having an extension adapted to extend into the first-mentioned tube, a packing gasket on the disk to form an air-tight 10 union with the tubes, a spring in the casing beneath the disk to hold the latter upwardly displaced as specified, an angular bracket secured for vertical adjustment to one side of 15 the casing and having a part overhanging the pin, said overhanging part having

stamped-out tongues, and an expansible element between the tongues whereby when said element is heated it will expand between the tongues to engage the pin and unseat the 20 valve downwardly to permit the escape of gas for ignition, the element serving to contract when the gas is extinguished, whereby the spring will act against the pin to again 25 cut off the supply of gas to the tip.

In testimony whereof I have signed my name to this specification in the presence of two subscribing witnesses.

JULIUS E. JARGSTORFF.
